ROBERT KLEIN, OF BROOKLYN, NEW YORK, ASSIGNOR TO KLEIN, FRANKFELDT AND ARNOFF, INC., A CORPORATION OF NEW YORK.

CONVERTIBLE CAP.

Application filed February 3, 1927. Serial No. 165,521.

This invention relates to caps and particularly to that type which may be converted from one having one type or style of material exposed to view, to one having other 5 types or styles of material exposed in the same manner.

Heretofore caps of this type have been made with parts on the inside unfinished and allowing the raw edges of the material to be 10 seen at certain points where the parts have been seamed together. My invention contemplates the provision of a cap which can be reversed and turned or manipulated in various ways whereby any one of the three 15 different types of material which are used in the cap may be exposed to view. In my improved construction no sweat band is needed, the material intended to come into contact with the head being preferably soil- 20 proof and water-proof. Finished edges are presented throughout the entire cap at all points inside and outside, so that the wearer may reverse the cap if he so desires and he may have the choice of exposing any one of 25 three different coverings to view, without adversely affecting the appearance or utility of the cap.

The above and other objects of my invention will be clear from the description which 30 follows and from the drawing, in which,

Fig. 1 is a vertical central lateral section of my improved cap, showing in dotted lines how the cap may be converted into one with a different crown and visor fabric.

Fig. 2 is a perspective view of the same, showing the flap partly turned up to expose the underlying parts, and

Fig. 3 is a horizontal section through the lateral seams.

In the practical embodiment of my invention illustrated, I prefer to provide three distinct crowns 10, 11 and 12. Each of said crowns may be made of a different type of material to widen the range from which the 45 wearer may choose on the proper occasion. For instance, the crown 10 is preferably made of dark silk, the crown 11 of white or colored, striped or checked fabric such as might match the overalls or other garments 50 of the wearer, and the crown 12 of suitable water-proof material such as leather, glazed or leatherized fabric or imitation leather. To construct and shape the crowns at the least expense, I prefer to form each of said 55 crowns of four sectors each of the same size

and shape as the other sectors of the same crown and as the sectors of the other crowns. At least two sectors of each crown may be 60 seamed together to form crown halves which are later combined in pairs in the three possible permutations, as will be hereinafter more fully described.

The visor 13 is covered on one side with the same material as that of the crown 10, which in this case is black silk or similar 65 fabric 14 which does not show soil marks or the marks of perspiration and the like due to contact with the head of the wearer. On the other side, the visor 13 is covered with leather or imitation leather 15 such as is 70 used in the crown 11, and suitably treated to give said material water-proof properties, and adapted to be washed when desired to remove soil marks.

The visor 13, however, may be covered 75 with either of the other two combinations of material if desired, or with different material entirely, though I prefer to use the dark material on one side and the water-proof material on the other as described above. 80

Each of the crowns may be made up separately by sewing together the lateral and transverse edges of the four sectors thereof on the reverse side, as by the lateral stitching 85 29 and 30 and similar transverse stitching or the crowns may be made in halves, which are then ready to be secured to each other and in part to the visor in a permutation series as 11—10; 10—12; and 11—12, as will now be described.

After the crowns 11 and 12 or the halves thereof have been formed, the lower rear edges 16 of said crowns are seamed together by the stitching 17. The seamed edges 20 of the crown 10 may then be stitched to the 90 seamed edges 21 and 22 of the respective crowns 11 and 12 at the transverse seam 18 by the transverse stitching 19 running completely across the cap or certain of the crown halves may be so stitched together 95 and the seamed edges of one of the crowns may be left unseamed by the stitching 19 as will be obvious. If desired however, the various crowns may first be made in halves 100 and then all or some of the various half crown edges 20, 21 and 22 may be sewn together by the stitching 19 transversely, after which the edges 16 of the crowns 11 and 12 may be 105 turned in and seamed together.

It now remains only to seam together the 110

lower front edges 23 of the crowns 10 and 11 by the stitching 24, and to insert the covered visor 13 between the lower front edges 25 of the crowns 10 and 12 and finally to secure the visor in place and to finish the cap by the lower front stitching 26.

It will be noted that by means of my improved construction, all of the raw edges of the various sectors and the visor are concealed on the inside of the cap, and that a flap 28 is provided unattached to the visor at its lower edge 23, but otherwise secured in place by the stitching 19. Since the material used for the crowns 10 and 12 is either washable or of the kind that does not show soil marks, no sweat band is needed. There is no right or wrong side to the cap, since it may be used equally well when turned inside out from any position thereof.

20 The flap 28 is so arranged that the material of the crown 11 which may not be soil or water-proof is always either on the outside as shown by the full lines of Fig. 1 or folded into adjacent halves not arranged to contact with the head as shown by the dotted lines of Fig. 1 whereby the crown 11 may be kept clean indefinitely.

If it is desired to convert the cap into one showing the crown 11 together with the water-proof material of the visor 13, said visor is merely moved from the front to the rear of the cap as indicated by the dotted lines of Fig. 1. To bring the crown 12 on the outside of the cap, the flap 28 is thrown over from the front to the rear about the stitching 19, and the entire cap turned inside out, thereby maintaining the crown 11 in its unsoilable position; or the visor may be moved to the rear as indicated by the dotted lines, 40 and the resulting flap composed of the crown halves 12 and 11 may be turned over from what was formerly the rear of the cap to what was formerly the front. In none of the three or more possible positions of the 45 cap are any unfinished edges presented either on the outside or on the inside.

It will be seen that I provide a simple, neat and easily and economically constructed cap of finished appearance throughout 50 adapted for manipulation into positions giv-

ing at least three different aspects, and that while the invention is illustrated in connection with caps usually used by locomotive engineers, it may equally be used in connection with caps of other types. Various other changes are contemplated and may be made in the illustrated embodiment of my invention, it being my intention to claim the same as broadly as will be permitted by the state of the prior art.

I claim:

1. In a cap of the character described, six half crowns, seamed to conceal the raw edges thereof, stitching securing the lower edges of said crown halves together in pairs to form three separate flaps, the pair of crown halves of each of said flaps forming a different combination from the pair in each of the remaining flaps, and a visor seamed in place between the lower edges of the crown halves of one of said flaps, the other flaps being completely free of said visor.

2. In a cap of the character described, three crowns of different materials, any one of said crowns being adapted to serve as the lining of the cap, and any one of said crowns being adapted to be so arranged as to be at all times out of possible contact with the head of the wearer, each of said crowns consisting of two halves of substantially the same size and shape, stitching joining the crown halves together at their lower edges in pairs to form three separately and independently movable flaps free at their lower edges, each flap comprising a pair of different crown halves differing as to material from the pair of crown halves of the remaining flaps, the flaps being arranged so that the crown halves of the same material are adjacent to each other on the outside or on the inside of the cap, and a visor secured to and between the inturned lower edges of one of the flaps and free and independent of the other flaps, whereby said visor may be moved to either end of the cap when the flap to which it is attached is intermediate of the other flaps.

ROBERT KLEIN.
